UNITED STATES PATENT OFFICE.

EMMETT W. STULL, OF MILWAUKEE, WISCONSIN, ASSIGNOR TO ALLIS-CHALMERS COMPANY, A CORPORATION OF NEW JERSEY.

COVER-FASTENER.

1,047,588.

Specification of Letters Patent. Patented Dec. 17, 1912.

Application filed March 31, 1910. Serial No. 552,693.

To all whom it may concern:

Be it known that I, EMMETT W. STULL, a citizen of the United States, residing at Milwaukee, in the county of Milwaukee and State of Wisconsin, have invented certain new and useful Improvements in Cover-Fasteners, of which the following is a full, clear, and exact specification.

My invention relates to an improved latch or clamp for holding a movable lid or cover in position.

The object of my invention is to provide a simple, efficient, and novel latch or clamp for securing and retaining covers in position regardless of the amount of vibration or wear produced in the use either of the latch or of the portion of the cover with which it engages.

One important application of my invention is found in connection with railway motors which are entirely inclosed or practically so. Such machines are usually provided with openings through the frames or casings by means of which access can be had to the commutator or other parts of the machine. These openings are normally covered by plates or covers which are somewhat larger than the openings and which are usually fastened in position by a latch at the respective ends and adapted to engage projections on the cover.

In order to prevent chattering of the cover when the motor is in operation strips of felt are placed between the cover and the main part of the casing, and the latches arranged to coöperate to hold the cover firmly in place. With this arrangement chattering is temporarily prevented, but due to the felt wearing out and being pressed thinner by constant jarring and getting wet, it is customary to provide means which will automatically keep the cover secured tightly to the casing.

By means of this invention, provision is made for effectively retaining a cover in position even after it has been in service a great length of time and without necessitating any particular trouble in adjusting the latch mechanism for holding the cover in place.

In the accompanying sheet of drawings, Figure 1 is a fragmentary top elevation of a railway motor equipped with my invention; and Fig. 2 is a sectional view taken 55 along the line 2-2 of Fig. 1.

With motors, and especially railway motors which are in constant use and are subjected to severe jarring while in operation, it is necessary to inspect the parts within the casing at frequent intervals to see the condition of the several parts. For this reason an opening provided with a cover 31 is formed in the motor casing 10. When the motor is in operation it is necessary that the cover 31 be secured tightly to the motor casing and fit in a manner to prevent the admission of dust or foreign particles, which would be injurious to the efficient working conditions of the motor.

The cover 31 is provided with flanges 32 and 33 which form a groove for the reception of some yieldable material such as felt 34. The felt is interposed between the casing and the cover so that when the latter is secured to the casing there is a springy effect. Chattering would occur also were it not for the use of some springy material located between the casing and cover 31. This cover is further provided with a plurality of forked end portions or projections 35 and 36, which are located opposite to each other, and preferably at the ends of the cover.

Secured to the casing is a receptacle 37 which is provided, preferably, with a hollow squared portion 38 for the reception of a coil spring 39. Passing through this coil spring and through an opening 40 in the upper part of the receptacle 37 is a bolt or plunger member 41, which is provided with a head 42 and a threaded portion 43, which is engaged by a special nut 44. On the opposite side of the casing I have provided a similar spring pressed latch 45 which is secured to the casing by a pivot 46 and has a handle 47. These members, which are located on opposite sides of the casing and secured thereto, are adapted to engage the forked end portions of the cover 31 to secure said cover in position. When the cover is removed from the casing and it is desired to place it back into position, the forked end portion 35 is slipped under the nut 44 thus drawing up the plunger and compressing the spring 39. The other end of the cover is then placed in position and the latch 45 is swung about its center 46 and is brought into engagement with the forked end portion 36, also drawing up the other plunger 41 and compressing the coil spring 100

39. A projection 48 in the handle 47 engages a hollow portion 49 of the forked end portion 36 to hold the latch in a locked position. When the latch is in this position the 5 felt 34 between the casing and cover 31 is compressed to a desirable degree and the cover is held firmly. The cover will always be held closely and firmly secured to the casing due to the stored energy in the coil 10 spring 39. In case the spring becomes weak or the felt becomes worn and it is desired to retain the cover more tightly to the casing, the keyed nuts 44 on the plungers can be adjusted to compress the springs to a 15 greater degree.

It is apparent that the cover 31 can be easily and readily removed and again replaced in a very short time. When the cover 20 is secured in place it is held rigidly and in a manner to prevent the admission of any undesirable foreign matter. By means of this construction a novel and useful arrangement is obtained.

It is further evident that there may be

many modifications of the precise form and arrangement herein shown and described, and I aim in my claim to cover all such modifications which do not involve a departure from the spirit and scope of my invention.

What I claim as new is:

In combination, a casing having a cover with projections on opposite sides thereof, receptacles mounted on said casing, one of said receptacles being pivoted thereto, resilient members located in said receptacles, bolts associated with said resilient members, and threaded adjustable members engaging said bolts and said projections to retain the cover in a fixed position and to vary the 40 effectiveness of said resilient member.

Milwaukee, Wisconsin, March 21, 1910.

In testimony whereof I affix my signature, in the presence of two witnesses.

EMMETT W. STULL.

Witnesses:

CHAS. L. BYRON,

ROB. E. STOLL.
